UNITED STATES PATENT OFFICE.

MESROPE DAVID, ZAKAR DAVID, HARRY DAVID, AND PAUL DAVID, OF BROCKTON, MASSACHUSETTS.

DESIGN FOR A CHISEL, NAIL-PULLER, AND HAMMER.

SPECIFICATION forming part of Design No. 35,652, dated February 4, 1902.

Application filed December 11, 1901. Serial No. 85,499. Term of patent 14 years.

To all whom it may concern:

Be it known that we, MESROPE DAVID, ZAKAR DAVID, HARRY DAVID, and PAUL DAVID, citizens of Turkey, all having applied for citizenship of the United States, residing at Brockton, in the county of Plymouth and State of Massachusetts, have invented and produced a new and original Design for a Chisel, Nail-Puller, and Hammer; and we do hereby declare the following to be a full, clear, and exact description of the same, reference being had to the accompanying drawings, forming a part thereof.

In the drawings, Figure 1 is an elevation in side view of a chisel, nail-puller, and hammer, showing our design. Fig. 2 is a top or plan view of the same.

As shown in the drawings, *a* represents the chisel and its cutting edge *b*, *c* the stock or part which receives the handle *d*, and *e* the hammer-head, these parts *a*, *c*, and *e* being formed in one piece.

In the flat or upper face of chisel *a* is made a nail-puller *f*, having a hole to admit a nail-head and beveled edges 2 2, converging toward the stock *c*, as shown. 25

The hammer-head *e* projects from the stock *c* at one side of the handle, and, as shown, the chisel projects inclined and at its opposite side. 30

Having described our invention, what we claim as new, and desire to secure by Letters Patent, is—

The design for a chisel, nail-puller, and hammer, as herein shown and described. 35

In testimony whereof we affix our signatures in presence of two witnesses.

MESROPE DAVID.
ZAKAR DAVID.
HARRY DAVID.
PAUL DAVID.
